US00D617630S

(12) **United States Design Patent**
Mansikkamaa

(10) **Patent No.:** **US D617,630 S**
(45) **Date of Patent:** **** Jun. 15, 2010**

(54) **HANGING OR STORAGE ATTACHMENT FOR A SINK**

D190,952 S * 7/1961 Blum D25/38
D216,458 S * 1/1970 Nestruck D8/363
D219,573 S * 12/1970 Welss D8/363
D222,799 S * 1/1972 Gorishek D8/354
D228,380 S * 9/1973 Gorishek D8/364

(75) Inventor: **Miika Mansikkamaa**, Nummela (FI)

(73) Assignee: **Magisso Oy**, Lohja (FI)

(**) Term: **14 Years**

* cited by examiner

(21) Appl. No.: **29/311,022**

Primary Examiner—Robert M Spear

Assistant Examiner—Barbara B Lohr

(22) Filed: **Dec. 10, 2008**

(74) *Attorney, Agent, or Firm*—Dennison, Schultz & MacDonald

(30) **Foreign Application Priority Data**

Jun. 11, 2008 (EM) 00949151-0001
Jun. 11, 2008 (EM) 000959226-0001

(51) **LOC (9) Cl.** **08-05**
